UNITED STATES PATENT OFFICE.

WILLARD F. MILLS, OF WELLINGTON, OHIO, ASSIGNOR TO HIMSELF AND
JOHN J. THOMAS, OF SAME PLACE.

MUSIC-RACK.

SPECIFICATION forming part of Letters Patent No. 227,034, dated April 27, 1880.

Application filed October 6, 1879.

To all whom it may concern:

Be it known that I, WILLARD F. MILLS, of Wellington, in the county of Lorain and State of Ohio, have invented certain new and useful Improvements in Music-Racks; and I do hereby declare the following to be a full, clear, and exact description of the invention, such as will enable others skilled in the art to which it pertains to make and use it, reference being had to the accompanying drawings, which form part of this specification.

My invention consists in the combination, with a suitable base and a holder formed with a continuous bearing portion having end arms, of a fastening device which pivots the latter to the base, and springs respectively located on the outer side of the two arms, said springs extending outward from the arms to their points of attachment to the base.

In the drawings, Figure 1 is a perspective view of the device applied as in use. Fig. 2 is a detail plan view of the same.

The spring-holder G is made with a continuous bearing portion, g, provided with end arms, g'. A staple, g², secures the latter to the base F and permits them to have pivotal movement thereon.

Springs g³ are respectively located on the outer side of the two arms, and extend therefore from diagonally outward to the points of their

attachment to the base. This spring-holder may be held in closed position against the music or book upon the rack; or it may be thrown in open position upon the base.

It is apparent that the music-rack and tripod herein shown do not restrict my invention to use solely with them; but the spring-holder can be connected to any suitable instrument—a piano, for instance. So, also, it is evident that any suitable device or support adapted to provide a base for the attachment of the holder may be employed.

Having described my invention, what I claim is—

The combination, with a base and a holder formed with a continuous bearing portion having end arms, of a fastening device which secures the latter in pivotal movement on the base, and springs respectively located on the outer side of the two arms, said springs extending outwardly from the arms to their points of attachment to the base, substantially as set forth.

In testimony whereof I have signed my name to this specification in the presence of two subscribing witnesses.

WILLARD F. MILLS.
